STEMMING WAD FOR BLASTHOLES

Burton A. Olsen, Oakland, Calif., assignor to California Cotton Mills Company, Oakland, Calif., a corporation of California

Application March 5, 1940, Serial No. 322,315

3 Claims. (Cl. 102—30)

This invention relates to prepared wads of resilient material used as tampons for closing recesses or apertures.

It is an object of the invention to provide a stemming wad which is fireproof.

Another object of the invention is to provide a stemming wad which is not buoyant and therefore will not be carried in sump water into the intake ducts of pumps where it might foul the intake valves of the pump and incapacitate the latter.

The invention possesses other objects and features of advantage which will be brought out in the detailed description of the invention hereunto annexed. It is to be understood that the invention is not to be limited to the specific form thereof shown and described as variants thereof may be employed within the scope of the appended claims.

Referring to the drawing:

The figure is a view, partly in side elevation and partly in vertical section, showing the stemming wad of my invention.

In the drawing I have shown the preferred form of my invention. In this case I pre-form a wad of cotton or other fibers 9 and then either dip the wad into a liquid bath which will deposit a surface coating 11 on the wad or, preferably, I spray the liquid on to the wad so as to form the coating. The coating material is composed of a liquid vehicle, which in itself is capable of rendering the fibrous material fireproof or highly resistant to combustion, such as fluid solutions of alum, borax, sodium silicate, sodium tungstate or zinc chloride. Preferably however the liquid vehicle is composed of a material which is both fireproof and insoluble in water such as a fluid phenol or aldehyde resin the nature of liquid "Bakelite." In this fluid vehicle is mixed, preferably, metallic powder such as aluminum, bronze, etc. Sufficient of the liquid is sprayed on to the surface of the fibers 9, or deposited on the surface by dipping the wad in a bath of the fluid material, to provide a coating in which sufficient metallic material is contained to overcome the buoyancy of the cotton and to cause it to sink when placed in water. Thus, if the wad, after being used in a blast hole, should happen to find its way into water drainage ducts, it will be too heavy to be carried by the water into the mine pump and there possibly clog the intake or exhaust valves so that the pump will be rendered inoperative. It will be seen that the reason for providing a waterproof coating material is to exclude the possibility, should the wad become

immersed in water, of the water dissolving the coating and thereby rendering the wad buoyant so that it may be carried by the water current into the pump.

5 After the blasting charge has been placed in the hole, and the blasting cap and fuse have been placed, the stemming wad is inserted in the hole and driven home by the ramrod. After being bottomed, the wad is forcibly tamped by the ramrod. This compresses the cotton causing the mass of the latter to expand radially and force it into any pits or irregularities in the bore hole so that the wad is thus securely locked in the hole. It will be seen that the fuse may burn past the wad without setting the latter afire since the coating and the metal particles embedded therein shield the cotton from being ignited. The coating also protects the cotton against ignition by the flash of the blast.

20 During cleaning up of debris after the blast, should the stemming wad happen to find its way into the ditches carrying off seepage water, it will not be borne by the water into the pump sumps since the heavy metal in the coating will preclude this by rendering the wad incapable of floating in the water.

25 Due to the fact that it is fireproof, the stemming wad of my invention may be safely used in coal mines or, in other operations where inflammable dust is present, since it may not be ignited by either the burning fuse or the flash of the blast and thereby possibly cause ignition of the dust. Also, due to the presence of the relatively stiff coating covering the fibrous material, the stemming wad may be more tightly packed in the blast hole than may a resilient wad of untreated fibers thus causing the wad to more tenaciously grip the sides of the bore. Furthermore, the fibrous wad provides a shock absorber between the end of the ramrod and the firing cap which greatly lessens the danger of premature blasts due to accidental discharge of the cap by shock.

30 Having thus described my invention in detail, what I claim as new and desire to secure by Letters Patent is:

1. A tamping wad of the class described having a shaped body and a covering therefor, the entire body being formed of fibrous material and comprising a mass of unimpregnated loosely aggregated fibers, the covering completely enveloping the body and adhering to and constituting a binder for the fibers at the exterior of said body, said covering being fireproof, insoluble in water and including a sufficient quantity of comminuted

metal to overcome the natural buoyancy of the body of fibrous material and thereby to cause the body to sink when placed in water.

2. A tamping wad of the class described having a shaped body provided with a skin coating, said body being formed entirely of fibrous material and comprising a mass of unimpregnated loosely aggregated fibers, the skin coating completely enveloping the body and adhering to and constituting a binder for the fibers at the exterior of said body, said skin coating being insoluble in water and including a sufficient quantity of comminuted metal to overcome the natural buoyancy of the body of fibrous material and thereby to cause the body to sink when placed in water.

15

3. A tamping wad of the class described having a shaped body provided with a skin coating, said body being formed entirely of fibrous material and comprising a mass of unimpregnated loosely aggregated fibers, the skin coating completely enveloping the body and adhering to and constituting a binder for the fibers at the exterior of said body, said skin coating being formed of fireproof material and including 5 a sufficient quantity of comminuted metal to overcome the natural buoyancy of the body of fibrous material and thereby to cause the body to sink when placed in water.

BURTON A. OLSEN.
